LOADING MACHINE

Gilbert E. Coats, Fort Dodge, Iowa

Application May 29, 1944, Serial No. 537,945

7 Claims. (Cl. 214—141)

1

This invention relates generally to loading machines and in particular to a machine for picking up and stacking or loading hay, manure and like material.

An object of this invention is to provide an improved tractor-loading machine.

A further object of this invention is to provide a loading machine which is capable of being easily and quickly mounted on different types of farm tractors and operated from the usual tractor power take-off.

Yet another object of this invention is to provide a tractor-mounted loading machine in which the load is supported on extensible pivoted members and elevated by overhead lifting means in a substantially upright direction so that practically all of the available lifting force is efficiently applied to lifting the load.

A still further object of this invention is to provide a tractor-mounted loading machine which is of a unit construction and readily removed from and assembled on the tractor so as to appreciably decrease the over-all time for a loading operation and in turn increase the availability of the tractor for other farming operations.

Another object of this invention is to provide a tractor-mounted loading machine which is of a light weight and compactly assembled on the tractor so as not to interfere with the operator's visibility whereby the normal operating economy and ease of handling of the tractor is maintained during its use for loading purposes.

A feature of this invention is found in the provision of a tractor-mounted loading machine in which a pair of extensible lifting arms are positioned at opposite sides of the tractor and pivoted at their rear ends for pivotal up and down movement. A load-carrying means is mounted between the forward ends of the arms and is movable upwardly in guiding engagement with an upright frame positioned between the forward ends of the arms. To accommodate the machine to different size and type tractors means are provided for adjusting the upward inclination of the uprights and the position of the load-carrying means in a substantially horizontal plane at its lowermost position of travel.

A further feature of this invention is found in the provision of a tractor-mounted loading machine in which a pair of elongated arms having extensible front portions are positioned at opposite sides of the tractor and pivoted adjacent their rear ends for up and down pivotal movement. Uprights are supported on the tractor between the arms and rearwardly of a load-carrying means

2

supported between the extensible front portions of the arms. These front portions are connected with a flexible lifting means depended from the uprights and on lifting of the flexible means the front portions are extended to provide for an upward travel of the load-carrying means adjacent to the uprights.

Yet another feature of this invention is found in the provision of a tractor-mounted loading machine in which a load-carrying means is pivotally supported between the free ends of pivoted and liftable elongated members and provided with an upwardly and rearwardly projected lug member. A latch member is pivotally supported on and between the liftable members for movement into and out of locking engagement with the lug member, with the latch and lug members constituting the entire trip mechanism for the load-carrying means. The latch member is manually actuated through lever means and a pull cord which is extended rearwardly of the tractor and within easy reach of the tractor operator.

Further objects, features and advantages of this invention will become apparent from the following description when taken in connection with the accompanying drawings in which:

Fig. 1 is an elevational view of the loading machine of this invention shown with a manure fork and mounted on a tractor of usual type;

Fig. 2 is a front elevational sectional view of the machine as seen along the line 2—2 in Fig. 1;

Fig. 3 is a plan view of the lower pivoted frame of the loading machine removed from the tractor;

Fig. 4 is a sectional view on the line 4—4 in Fig. 3;

Fig. 5 is a sectional view on the line 5—5 in Fig. 3;

Fig. 6 is a fragmentary plan view of the trip mechanism for the manure fork;

Fig. 7 is a sectional view as seen along the line 7—7 in Fig. 6;

Fig. 8 is a perspective view of an adjustable member used in the trip mechanism;

Fig. 9 is a perspective view of an actuating rod used in the trip mechanism;

Fig. 10 is an enlarged detail view of the clutch and brake mechanism for the loading machine as seen along the line 10—10 in Fig. 1;

Fig. 11 is an elevational sectional view of the clutch and brake mechanism as seen along the line 11—11 in Fig. 10;

Fig. 12 is an elevational view of the loading machine, illustrated similarly to Fig. 1, showing the machine in changed position and with a buck rake;

Fig. 13 is a fragmentary plan view of the trip mechanism for the buck rake;

Fig. 14 is a sectional view taken along the line 14—14 of Fig. 13; and

Fig. 15 is a rear plan perspective view of the 5 hay buck illustrated with the loading machine in Fig. 12.

With reference to the drawings the loading machine of this invention is illustrated in Fig. 1 mounted on a farm tractor of a usual type having a body frame or chassis 20, rear wheels 16 and front steering wheels 17. The steering mechanism for the wheels 17 includes steering arms 18 connected with a steering rod 19 through a gear box 21, the steering rod 19 being extended 10 toward the rear of the tractor and provided with a suitable steering wheel (not shown) at its rear end. A usual power take-off, indicated at 22, is mounted forwardly of the rear wheels.

The loading machine includes a lower pivoted 20 frame comprised of a substantially U-shaped member 23 having its legs 24 positioned at opposite sides of the tractor frame 20 (Figs. 1 and 3). The U member 23 is of a tubular construction and has its base portion rotatably supported in bearings 27 which are carried on an inverted channel member 28 suspended from a supporting structure located at the rear end of the tractor. The supporting structure is comprised of a pair of angle members 29 depended from each side 30 of the tractor frame 20 and connected together at their lower ends by an angle member 31, the channel member 28 being connected to and extended between the angle members 31.

Each bearing 27 is of a two piece construction 35 with the mating halves secured together at one end and to the channel member 28 by a nut and bolt assembly 33 and at their opposite ends by lock nuts 34 threaded on a brace rod 36, which will be explained later (Fig. 4). By virtue of the 40 pivotal support of the U member 23, it is apparent from a consideration of Figs. 1 and 3 that the leg members 24 are pivotally movable up and down at opposite sides of the tractor frame.

The leg members 24 are in telescoping arrangement with tubular sleeve members 37 and 37a which are movable to adjusted positions relative to the forward end of a corresponding leg member 24 (Fig. 5). The movement of a sleeve member 37 and 37a in a direction rearwardly of the leg members 24 is defined by a stop pin 38 which is receivable in aligned openings 39 formed in a spaced relation axially of a leg member 24. It is thus seen that the sleeve members 37 and 37a are freely slidably movable relative to a corresponding leg member 24 in a forward direction while their movement in a rearward direction is limited by their engagement with the pins 38 for a purpose which will become apparent later on. The forward ends 39a of the sleeve members 37 and 37a are bent flat, as clearly appears in Fig. 3, with each forward end having a bolt or shaft 41 mounted therein. A load-carrying means 42, illustrated as a manure fork, in Figs. 1, 2 and 3, is pivotally supported on the pins 41 between the forward ends of the sleeve members 37 and 37a.

With reference to Figs. 3 and 6 it is seen that the forward ends of the sleeve members 37 and 37a are connected together by means including a tubular transverse beam 43 the opposite ends of which are flattened and then welded to the underside of corresponding members 37 and 37a. A second transverse supporting member 44 of angle iron construction is inverted and extended 75

between the forward ends of the sleeve members 37 and 37a forwardly of the tubular beam 43, and is welded at each end to the upper sides of the sleeve members 37 and 37a. Supported on the transverse angle member 44, and substantially intermediate its ends is an adjustable member 45 which is movable to adjusted positions laterally of the transverse angle member 44.

As shown in Fig. 8 the adjustable member 45 is of a substantially channel-shaped construction having flanges 47 projected outwardly from the free end of each of its legs. Each flange 47 is formed with an elongated slot 48 which slots are adapted for alignment with corresponding elongated slots 49 provided in the transverse angle member 44. Bolts 51 are receivable within a corresponding pair of aligned slots 48 and 49, with the adjustment of the member 45 being accomplished by manipulation of the bolts 51 in a usual manner.

Pivots supported at one end on the leg 52 of the adjustment member 46, and located within the member 46 is an elongated latch member 53, which extends upwardly and outwardly from the member 46 into an engaging position with a lug or catch member 54 secured to the upper rear end of a manure fork 42. The latch 53 and the catch 54 are shown in a closed position in Figs. 6 and 7. The release or trip mechanism for the latch 53 includes an actuating rod 56 (Figs. 6 and 9) having a rocker arm 57 carried at one end thereof with the arm 57 being of a bifurcated construction at its free end 58. A lever 59 is mounted, intermediate its ends, at the opposite end of the rod 56.

The rod 56 adjacent the crank arm 57 is rotatably supported in an elongated slot 61 provided in an extension of the leg 62 of the adjustment member 46, with the arm 57 being located between the legs 52 and 62 of the member 46. The bifurcated portion 58 on the arm 57 is slidably received on a pin 63 carried on the latch 53. The rod 56 extends longitudinally of the cross member 44 and is rotatably supported adjacent the lever 59 in a member 60 which is adjustably supported on the angle member 44 in all respects similar to the adjustment member 46. In the assembly of the trip mechanism the rod 56 with the rock arm 57 thereon, is extended through the adjustment members 46 and 60 prior to the mounting of the lever 59 on the rod 56. The end 70 of the lever 59 is pivoted to one end of an actuating rod 75, the other end of which is pivoted to the free end of a lever 80, which is pivoted at 85 adjacent the rear end of the sleeve 37. A pull cord or cable 90 is connected to the free end of the lever 80 and extends toward the rear of the tractor to a position where it can be manipulated by the tractor operator.

As shown in Figs. 6 and 7 the latch 53 and catch 54 are in locked position which is retained by the action of a spring 65 connected at one end to the end 93 of the lever 59, and at its other end to a guide plate 93 which is carried on the sleeve member 37 and which will be later described. On pulling rearwardly on the cord 90, or to the left as shown in Fig. 1, and against the pressure of the spring 65, the levers 80 and 59 are pivoted in counter-clockwise direction, as also viewed in Fig. 1, to in turn rotate the rock arm 57 in a counter-clockwise direction, as also viewed in Fig. 1, to in turn rotate the rock arm 57 in a counter-clockwise direction as viewed in Fig. 7. During this rotation of the arm 57 the pin 63, on the latch 53, is slidably engaged and

moved by the bifurcated end 58 of the rock arm 57, to in turn move the latch 53 out of an engaging position with the lug 54, thus releasing the manure fork 42. After the fork 42 is dumped the lug 54 on the fork is returned to a locking position with the latch 53 by a spring 66 connected at one end to a top member 67 of an upright frame 68, and at its opposite or lower end to a cable 69 which in turn is connected to the manure fork 42 at 71 (Figs. 2 and 3).

The cable 69 is associated for travel about the under side of a pulley 72 which is rotatably supported in a bracket 73 carried on the transverse tubular member 44. On dumping of the fork 42 the spring 66 is extended by the weight on the fork, whereby its pressure is increased, and when the fork is emptied this spring pressure is sufficient to pivot the fork upwardly into locking position with the latch 53. It is seen, therefore, that the dumping of the fork 42 is manually controlled through the pull cord 90 while its return to a latching position is accomplished automatically by the action of the spring 66 and the cable 69.

The upright frame 68, previously mentioned, includes a pair of tubular upright members 74. The top member 67, to which the spring 66 is connected, constitutes the connecting or base member of a U-shaped tubular member having legs 82 each of which is adapted for telescopic assembly within the upper end of a corresponding upright 74 (Figs. 1 and 2). Each leg 82 is formed with a plurality of axially spaced oppositely aligned openings 83 for receiving a stop pin 84, whereby the U-shaped member is adjustably movable upwardly from the top ends of the uprights 74 and then held in an adjusted position by the bearing engagement of the pins 84 with the top of the uprights 74. By virtue of this vertical adjustment of the legs 82 the upright frame is extendible over a wide range to provide for a desired elevation of the fork 42.

The uprights 74 carry oppositely arranged supporting brackets 76 on their inner sides and adjacent their lower ends. The brackets 76 are of a channel iron construction and are welded to corresponding uprights 74. Each bracket 76 is pivotally supported at 77 to one end of a transverse beam member 78 which is secured to the forward ends of longitudinally extended members 79, the rear ends of which are connected by bolts 81 to the forward end of the tractor frame 20 so that the uprights 74 are pivotally movable together in a plane longitudinally of the tractor about their respective pivots 77.

Retention of the upright frame 68 in an adjusted position is accomplished by means including a second upright frame 86 located rearwardly of the upright frame 68 and comprised of a pair of uprights 87 and 87a, of an angle iron construction, secured at their lower ends to the longitudinally extending beams 79 and suitably supported in an upright position by brace members 88. A U-shaped clamp 89 is pivoted on a clamping bolt 91 at the top of each upright 87 and 87a. Extended through each clamp 89 is an adjustable rod 92 which has its upper end, as viewed in Figs. 1 and 2, pivotally connected at 93 to the top member 67 of the upright frame 68. On loosening of the clamping bolt 91 an adjustable rod 92 is slidably movable within a clamp 89 to provide for a free pivotal movement of the upright frame 68 to a desired position. This position is retained by merely tightening the clamp-

ing bolts 91 in a manner which is believed to be obvious.

In the description of the lower frame unit, shown in Fig. 3, it was mentioned that the sleeve members 37 and 37a were pivotally movable in an up and down direction at opposite sides of the tractor frame 20. The members 37 and 37a during this pivotal movement, are guided for movement in a substantially upright direction by the tubular uprights 74 which, as shown in Fig. 2, are positioned adjacent the sleeve members 37 and 37a and in a contacting relation therewith.

As best shown in Fig. 1 the lower ends of the uprights 74 are substantially at the level of the axle for the front tractor wheels 17 so that they adequately clear the ground when the tractor is travelling over a rough ground surface. However, when the fork 42 is in its loading position, shown in Fig. 1, the sleeve members 37 and 37a are below the level of the lower ends of the uprights 74. In order to secure a travel of the sleeve members 37 and 37a in a guiding relation with respect to the uprights 74 each sleeve member carries an upwardly projecting guide plate 93 adjacent its forward end and at a position opposite a corresponding upright 74.

The pivotal movement of the lower frame of the loading machine, and in turn an elevating of the fork 42, is accomplished by means including a cable 94 having one end connected to a yoke 96 which is pivoted at the upper ends of spaced brackets 98, the lower ends of which are suitably secured, as by welding, to the transverse tubular beam 43 extended between the sleeve members 37 and 37a (Figs. 1, 2 and 3). From the yoke 96 the cable extends upwardly and over a pulley 99 rotatably supported between spaced plate members 101 projected forwardly of and welded to the top member 67 of the upright frame 68. From the pulley 99 the cable 94 travels downwardly and about a pulley 102 rotatably supported between the brackets 98 and then upwardly and about a pulley 104 rotatably supported between the plate members 101 rearwardly of the pulley 99. From the pulley 104 the cable 94 travels to a winding drum 106 mounted on a driven shaft 107 rotatably supported in bearings 108 carried on the uprights 87 and 87a of the frame 86 (Figs. 1, 2 and 10).

Also mounted on the shaft 107 is a sprocket 109 which is connected by a sprocket chain 110 to a sprocket 111 integrally formed on a sleeve member 113 which is freely rotatable on a driving shaft 114 located below the shaft 107 and rotatably supported in bearings 116 and 116a secured to the uprights 87 and 87a, respectively. Also integral with the sleeve member 113 is a shell member 117 which constitutes one of the units in a friction clutch mechanism indicated generally at 118. The other clutch unit 119 is of a conical shape, adapted to be received in frictional engagement within the shell 117, and mounted on the driving shaft 114. By moving the clutch unit 117 axially of the shaft 114 into and out of frictional engagement with the clutch unit 119 power is transmitted from the shaft 114 to the shaft 107 through the sprocket and chain assembly 109-111.

This movement of the clutch unit 117 relative to the cone clutch unit 119 is accomplished by a clutch lever 121 integrally formed with a hub portion 122 which is rotatable on the driving shaft 114. The hub 122 is formed with a cam surface 123 for operative association with a corresponding cam surface 124 formed on the inner

side of the bearing member 116. As best shown in Fig. 10 the bearing member 116, hub 122 and sleeve member 113 are in a stacked relation on the driving shaft 114. Thus on pivotal movement of the clutch lever 121 in a direction rearwardly of the tractor, or toward the left, as viewed in Fig. 11, the sliding engagement of the cam surfaces 123 and 124 moves the hub 122 and sleeve 113 toward the right, as viewed in Fig. 10, to in turn move the shell 117 axially on the shaft 114 into frictional engagement with the cone 119. Since the cone 119 continuously rotates with the driving shaft 114 this frictional engagement of the units 117 and 119 connects the shaft 107 with the shaft 114 through the sprocket and chain assembly 109—111. The shaft 114 carries a pulley 126 which is connected through a belt 127 with the power take-off 22 (Fig. 1).

The connection and disconnection of the shafts 107 and 114, and the retention of the fork 42 at any elevated position, is controlled entirely by the manipulation of the clutch lever 121 in a manner now to be described. With reference to Figs. 10 and 11 the lever 121 is shown with its upper or free end pivoted to an actuating rod 128 which extends toward the rear of the tractor and to a position conveniently accessible to the tractor operator. Pivoted at one end to the lever 121, and substantially intermediate the ends of the lever 121, is a link 129 the opposite end of which is pivoted at 131 to a bell crank 132 of an angulate shape.

The bell crank arm 133, to which the link 129 is pivoted, is of a substantially L-shape having a shaft portion 134 extended laterally from the free end of its short leg. Shaft 134 is rotatably supported in a bearing 136 mounted on an angle iron member 137 extended between the frame members 79 and below the uprights 87 and 87a. The other leg 138 of the bell crank 132 is extended forwardly from the shaft portion 134 and then laterally parallel to and away from the shaft portion 134. A brake band 139 is positioned about the upper half of the clutch unit 117 and has one end 141 pivoted to the free end of the arm 138 and an opposite end 142 pivoted on a bolt 143 secured to the angle member 137.

The brake 139 is normally held in frictional engagement with the clutch unit 117 by a spring 144 connected at one end to the upright 87 and at its opposite end to the free end of the bell crank arm 133. On actuation of the clutch lever 121 in a direction toward the rear of the tractor, or in a counter-clockwise direction, as viewed in Fig. 11, the bell crank 132 is moved in a counter-clockwise direction by the link 129, to in turn move the brake band 139 upwardly at its end 141. This movement of the brake band 139 releases its frictional engagement with the clutch unit 117. With the clutch unit 117 thus released, the fork 42 is free to move downwardly from any elevated position due to the action of gravity. On a continued movement of the clutch lever 121 in a counter-clockwise direction the cam surfaces 123 and 124 are relatively moved a distance sufficient to frictionally engage the clutch unit 117 with the clutch unit 119 in the manner above fully described.

When the clutch lever 121 is released the brake band 139 is immediately moved into braking position with the clutch unit 117 by the action of the spring 144. It is thus seen that the elevating of the fork 42, its retention in an elevated position, and its release for falling downwardly to the

ground is controlled entirely by the actuation of the clutch lever 121.

In the assembly of the loading machine of this invention on a tractor the sleeve members 37 and 37a are initially adjusted to an extended position relative to the forward ends of the leg members 24 until the transverse tubular beam 43 is located forwardly of the uprights 74. When this adjustment of the sleeve members 37 and 37a has been determined the pins 38 are inserted in the leg members 24 to limit the rearward movement of the transverse member 43 such that it is always located forwardly of the uprights 74 when the sleeve members 37 and 37a are in a fully retracted position, it being understood that the retracted position of the members 37 and 37a is defined by their engagement with the pins 38. By virtue of this adjustment the lower frame is readily applicable to tractors of different type regardless of their length and the location on the tractor frame of the pivot for the lower frame, which includes the members 37 and 37a. With the sleeve members 37 and 37a thus adjusted the manure fork 42 is pivotally adjusted on its pivots 41 until the fingers 48 thereof are located in a substantially horizontal plane as shown in Fig. 1. This adjustment of the fork 42 is accomplished by adjusting the members 46 and 63 relative to the transverse angle beam 43 to in turn vary the position of locking engagement between the latch 53 and the latch 54. With the fork 42 thus positioned the tractor is advanced forwardly for loading the fork 42. On the application of a pressure on the manure fork 42 in a direction toward the rear of the tractor the movement of the sleeve members 37 and 37a rearwardly of the leg members 24, and in turn the movement of the beam member 43 toward the uprights 74, will be limited by the stop pins 38.

On raising of the fork 42, by manipulation of the clutch lever 121 in the manner fully explained above, the uprights 74 are in contacting engagement with the sleeve members 37 and 37a. As the fork 42 is elevated the sleeve members 37 and 37a are progressively extended forwardly of the leg members 24. When the fork 42 has been elevated to a desired position it is dumped by actuating the lever 80 for the latch release mechanism, and then returned to a loading position by the action of the spring 66. On lowering of the fork 42 it may drop to the ground in a position considerably ahead of the upright frame 68, in other words at a position in which the rear ends of the sleeve members 37 and 37a are forwardly of the stop pins 38. However, on movement of the tractor forwardly to again load the fork 42 the sleeve members 37 and 37a are initially moved against the stop pins 38 to provide for a normal loading position of the fork 42 adjacent the uprights 74.

As a result the fork is always adjacent the upright frame 68 when it is initially raised whereby to decrease the tendency of the tractor rear wheels 16 being lifted from the ground during a raising operation. Further the fork is substantially below the cable support 101 so that a direct lifting force is applied on the fork. The pressure acting rearwardly on the sleeve members 37 and 37a and legs 24 during a loading and lifting operation of the fork 42, is applied on the brace rods 26 which are connected at one end to the bearing straps 27 and at their opposite ends to the tractor frame 28.

When the fork 42 is elevated it follows an upward path determined in part by the inclination 75 of the upright frame 68 relative to a vertical plane

extended transversely of the tractor. As the fork 42, therefore, is elevated it will be moved upwardly concurrently with an extension of the sleeve members 37 and 37a. This extension of the sleeve members 37 and 37a is the result initially of the load-carrying means 42 tending to assume a position vertically below the support 101 for the cable 94. However, as the load-carrying means approaches its uppermost position a slideable engagement may occur between the tubular cross beam 43 and the front sides of the uprights 74. When this slideable engagement takes place, therefore, the extension of the members 37 and 37a is primarily the result of the slideable engagement between the member 43 and the uprights 74.

Under some conditions of operation the slideable engagement between the cross beams 43 and the uprights 74 may approach proportions such that an excessive side pressure is applied against the upright frame 68 as well as an increase in the force required to raise the fork 42, due to the resultant frictional pressure between the cross beam 43 and the uprights 74. To reduce this frictional pressure as much as possible, when the load-carrying means 42 approaches its uppermost position, the upright frame 68 is adjustable in a direction rearwardly of the tractor so as to permit a greater travel upwardly of the load-carrying means 42 before any appreciable contact takes place between the cross beam 43 and the uprights 74.

When the tractor with the loading machine thereon is to be moved from farm to farm or over the highways the upright frame 68 is inclined to a maximum position toward the rear of the tractor so as to appreciably decrease its over-all height. The fork 42 is then elevated to a position above the tractor frame 20 so as to have sufficient clearance with the ground. By virtue of the location of the clutch and lifting mechanism substantially ahead of the tractor, and with the upright frames 68 and 86 being of an open construction adequate visibility is provided to the tractor operator, and the upright frame 68 is lowered enough to freely clear any of the usual overhead obstructions such as telephone and electric wire lines.

With reference to Fig. 12 the loading machine of this invention is shown with a hay buck indicated generally at 150. Except for the hay buck the loading machine is the same in all respects as previously described so that similar numerals of reference will be used to designate like parts in Figs. 12, 13 and 14.

With reference to Fig. 15 the hay buck 150 includes a frame comprised of a rear cross member 151 of a tubular construction having substantially inverted U-shaped straps 152, illustrated as eight in number, supported on the beam 151 in an axially spaced relation. The legs of each strap 152 below the beam 151 are connected together by a brace plate 155. Secured to the bottoms of the forward legs of the straps 152 and substantially coextensive in length with the rear cross member 151 is a wooden beam 153. Connected to the bottoms of the rear legs of each outer pair of straps 152 is a wooden beam 154, and connected to the bottoms of the rear legs of the four center straps 152 is a wooden beam 156 so that spaces 157 are formed at the back end of the hay buck 150 between adjacent ends of the beams 154 and 156. The tines or prongs 158 of the hay buck are attached to the bottom sides of the wooden beams 153, 154 and 156. A wooden side guide 159 is supported at each end of the rear beam 151 in an angle member 161 welded to the beam 151.

The back of the hay buck includes upright angle members 162 welded to the rear leg of each strap 152. Back boards 160 are secured to the uprights 162 in a vertically spaced relation above the rear cross beam 151. Secured to the top of the beam 156 and to the four center straps 152 is an angle brace 163.

Welded between the rear legs of the inner pair of the four center straps 152 is an inverted channel member 164, to the top of which is welded a lug or catch member 166 (Figs. 14 and 15). Brace bars 167 for the catch member 166 are welded to the catch and to the inner pair of the four center straps 152. Laterally extended from each rear leg of the outer ones of the four center straps is an angle iron support 168 for an adjusting bolt 169. Each of such outer straps also has a spacer plate 171 welded to a corresponding brace plate 155, with an opening 172 being formed through a corresponding spacer plate 171 and brace plate 155 for a purpose now to be described.

In the assembly of the hay buck 150 on the loading machine, and assuming the manure fork 42 removed from the loading machine, the forward ends 39a of the sleeve members 37 and 37a are moved within the spaces 157 to positions adjacent the spacer plates 171. A bolt 41 is then extended through the end 39a of a sleeve member and through an opening 172 in a corresponding spacer plate 171 and brace plate 155. With the hay buck thus pivotally supported on the sleeve members 37 and 37a its upward pivotal movement is limited by the adjustment of the bolts 169. These bolts are in an engaging position with ledge portions or plates 173 welded to the tops of the sleeve members rearwardly from their forward ends. It is thus seen that the engagement of the bolts 169 with the plates 173 prevent the front end of the tines 158 from tilting upwardly when the hay buck is being loaded. On completion of this adjustment the latch 53 is moved into an engaging position with the lug member or catch 166 by adjustment of the members 46 and 60, in all respects similar to the adjustment of the latch 53 as described in connection with the manure fork 42 (Figs. 13 and 14).

The operation of the loading machine with the hay buck 150 is similar in all respects to its operation as described above in connection with the manure fork 42 so that a further description of such operation is believed to be unnecessary.

From a consideration of the above description it is seen that the invention provides a loading machine which is comprised of relatively few parts adapted for compact assembly on any type of tractor. The support of a load-carrying means on extendible pivoted members 37 and 37a provides for the load-carrying means always being in a position for direct lifting by an overhead lifting means, and for travel upwardly concurrently with an extension of the extendible members. The upright frame 38 on which the lifting means is supported is adjustably movable to inclined positions in a direction forwardly and rearwardly of the tractor so as to provide for the lifting of the load-carrying means with a minimum of interference from the upright frame. As a result the extension of the extendible pivoted members 37 and 37a is substantially accomplished entirely as a result of the lifting force applied at their free ends 39a.

Although the invention has been described with respect to a preferred embodiment thereof it is to be understood that it is not to be so limited since modifications and changes can be made

therein which are within the full intended scope of this invention as defined by the appended claims.

I claim:

1. A tractor-mounted loading machine comprising an upright frame supported on the tractor, telescoping members positioned at opposite sides of the tractor, means pivotally supporting said telescoping members adjacent their rear ends on said tractor for up and down pivotal movement, with said upright frame being positioned between the front ends of said telescoping members and said front ends extendible forwardly of said upright frame, load-carrying means mounted on said front ends forwardly of said upright frame, flexible load-lifting means supported from said upright frame and operatively connected with said front ends to raise said load-carrying means, means for raising and lowering said lifting means, and a frame member connected between said front ends adapted to contact the forward side of said upright frame, on upward pivotal movement of said telescoping members, to provide for the extension of said front ends as said telescoping members are elevated.

2. A loading machine adapted to be mounted on a tractor frame comprising an upright frame supported on the front end of said tractor frame, a pivoted lower frame of substantially U-shape having the legs thereof arranged at opposite sides of said frame, and the leg-connecting portion extended transversely of the tractor frame and below the rear end portion thereof, means suspended from said tractor frame for pivotally supporting said leg-connecting portion to provide for a pivotal up and down movement of said legs, a load-carrying means mounted on the free ends of said legs forwardly of said upright frame, and flexible lifting means depended from adjacent the top of said upright frame and operatively connected with said legs to lower and raise said load-carrying means.

3. In a tractor mounted loading machine, a pair of pivoted members at opposite sides of said tractor, means pivoting said members adjacent their rear ends on said tractor for pivotal movement in an up and down direction, means operatively connected with the forward ends of the pivoted members to raise and lower said forward ends, load-carrying means pivoted between the forward ends of said pivoted members, a lug member projected rearwardly and upwardly from said load-carrying means, a latch member, means supported between said forward ends for adjustable up and down movement, means pivotally supporting said latch member on said adjustable means for pivotal movement into and out of releasable locking engagement with said lug member, with adjustment of said adjustable means providing for the adjustment of said load-carrying means relative to the ground surface, a pin member extended laterally from said latch member, means for releasing said latch member including a rock shaft extended transversely of said pivoted members, an arm carried adjacent one end of said rock shaft slidably engageable with said pin member, and a manually operated lever mounted on said rock shaft adjacent its opposite end.

4. A loading machine for mounting on a tractor comprising a pair of telescoping frame units posi-

tioned at opposite sides of the tractor, means pivotally supporting said frame units at their rear ends on said tractor for pivotal movement in an up and down direction, with the front ends of said frame units being extendible forwardly of said frame units, load-carrying means mounted on said front ends, a first upright frame pivoted on said tractor between said frame units and rearwardly of said load-carrying means, a second upright frame on said tractor rearwardly of said first upright frame, means pivotally supporting said first upright frame for pivotal movement longitudinally of said frame units to an adjusted position, adjustable means connected between said first and second upright frames for supporting said first upright frame in an adjusted position, means on the front ends of said frame units for contacting said first upright frame to guide the pivotal movement of said frame units, and flexible lifting means depended from adjacent the top of said first upright frame and operatively connected with said front ends to raise and lower said load-carrying means, with said front ends being extended forwardly, as said load-carrying means is lifted, to provide for the travel of said load-carrying means upwardly adjacent said first upright frame.

5. In a loading machine for mounting on a tractor frame, a U-shaped frame having the legs thereof positioned at opposite sides of the tractor frame and extended outwardly beyond one end thereof, load-carrying means supported between the free ends of said legs, bearing members suspended from said tractor frame for rotatably supporting the leg-connecting portion of said U frame, means for pivoting said U frame to elevate said load-carrying means, and means connected between said bearings and said tractor frame to support said bearings against the pressure applied thereon by a load on said load-carrying means.

6. In a loading machine for mounting on a tractor, an upright frame located at one end of said tractor comprising a pair of tubular uprights supported on said tractor, an inverted substantially U-shaped member having the legs thereof receivable within the top ends of said uprights for telescopic assembly therewith, means for holding said U-shaped member in an extended position from the top ends of said uprights, and a flexible lifting means supported from the leg-connecting portion of said U member and operatively connected with a load-carrying means.

7. In a loading machine, a buck rake including a rear cross member, means for lifting said buck rake, a plurality of inverted substantially U-shaped members suspended from said rear member and spaced longitudinally thereof, a cross beam connected to the forward legs of said U members, support members connected across certain of the rear legs of said U members in a linearly spaced relation across the rear end of said buck rake, tines connected to said cross beam and support members, a side guide connected to each end of said rear member, and means located at the central portion of said cross beam and including a pair of said U members for pivotally supporting said buck rake adjacent its rear end on said lifting means.

GILBERT E. COATS.
